US00D769255S

(12) **United States Design Patent** (10) **Patent No.:** **US D769,255 S**
Karunamuni et al. (45) **Date of Patent:** **** Oct. 18, 2016**

(54) **DISPLAY SCREEN OR PORTION THEREOF WITH GRAPHICAL USER INTERFACE**

(71) Applicant: **Apple Inc.**, Cupertino, CA (US)

(72) Inventors: **Chanaka Karunamuni**, Cupertino, CA (US); **Stephen O. Lemay**, San Francisco, CA (US); **Marcel van Os**, San Francisco, CA (US)

(73) Assignee: **Apple Inc.**, Cupertino, CA (US)

(**) Term: **14 Years**

(21) Appl. No.: **29/500,267**

(22) Filed: **Aug. 22, 2014**

Related U.S. Application Data

(63) Continuation of application No. 29/449,303, filed on Mar. 14, 2013, now Pat. No. Des. 711,915, which is a continuation of application No. 29/424,274, filed on Jun. 10, 2012, now Pat. No. Des. 710,378, and a continuation of application No. 29/424,281, filed on Jun. 10, 2012, now Pat. No. Des. 711,911.

(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a display screen or portion thereof with graphical user interface showing our new design. The broken lines around the Figures show a display screen or portion thereof and form no part of the claimed design. The broken lines within the Figures show portions of the graphical user interface that form no part of the claimed design.

1 Claim, 1 Drawing Sheet
